CORE DRILL CONSTRUCTION

Filed Aug. 11, 1937

UNITED STATES PATENT OFFICE

2,123,453

CORE DRILL CONSTRUCTION

Alfred C. Catland, Alhambra, and Philip C. Efromson, Whittier, Calif., assignors to Globe Oil Tools Company, Los Nietos, Calif., a corporation of California

Application August 11, 1937, Serial No. 158,514

15 Claims. (Cl. 255—72)

This invention relates to well tools and relates more particularly to a core drill for use in the rotary method of well drilling. A general object of this invention is to provide a simplified, dependable and improved bit head construction for a core drill of the character mentioned.

Another object of this invention is to provide a practical, effective, anti-friction bearing means for mounting the roller cutters of a well core drill.

10 Another object of this invention is to provide a well core drill construction of the character mentioned in which the roller cutters are supported entirely by balls to rotate with a minimum of friction.

Another object of this invention is to provide a core drill construction of the character mentioned in which the several parts of the cutter mountings are securely and dependably fixed to the head or body of the bit.

20 Another object of this invention is to provide a core drill construction of the character mentioned in which the assembly of a cutter, its supporting pin and its several bearing elements are held against separation prior to being assembled 25 on the bit head whereby the cutter assembly may be shipped, stored, handled and installed as a unit.

Another object of this invention is to provide a core drill construction of the character mentioned embodying novel means for securing the 30 ends of the cutter bearing assemblies to the bit head.

35 A further object of this invention is to provide a ball bearing mounting for the roller cutter of a well tool in which the cutter is supported by spaced rows of balls, both of which assume the end thrusts in both directions as well as the radial thrusts.

The various objects and features of our invention will be fully understood from the following 40 detailed description of a typical preferred form and application of the invention, throughout which description reference is made to the accompanying drawing, in which:

45 Fig. 1 is a central longitudinal detailed sectional view of the lower portion of a core drill embodying the present invention. Fig. 2 is a bottom view of the drill showing the cutters in broken lines. Fig. 3 is an enlarged fragmentary vertical 50 detailed sectional view illustrating one of the outer cutters and its mounting. Fig. 4 is a view similar to Fig. 3 showing one of the inner cutters and its mounting. Fig. 5 is a reduced side elevation of the C-washer of the bearing means 55 for one of the inner cutters. Fig. 6 is a reduced

side elevation of the sectional bushing of the bearing means for one of the inner cutters, and Fig. 7 is an end view of the bushing shown in Fig. 6.

The improved construction of the present invention may be embodied in core drills varying considerably in character. In the following detailed description we will describe the invention embodied in a core drill of the general character described and claimed in the copending application Serial No. 95,513, filed by Alfred C. Catland on August 12, 1936, for "Core drill", which has matured into Patent No. 2,093,633 granted Sept. 21, 1937. It is to be understood that the invention is not to be construed as limited or restricted 15 to the specific form or application about to be described.

The core drill illustrated in the drawing includes an outer barrel 10 to be connected with the lower end of a rotary well drilling string. 20 A bit head 11 is threaded on the lower end of the barrel 10. The bit head 11 is tubular having a central longitudinal opening 12 and the lower portion of the head 11 embodies certain features of the invention, as will be hereinafter described. 25 Spaced upwardly facing annular shoulders 13 and 14 are provided in the head opening 12. The drill further includes an inner barrel 15 extending longitudinally through the outer barrel 10 and adapted to receive the core. A collar 16 is 30 fixed on the lower end of the inner barrel 15 and is received between the shoulder 14 and a downwardly facing shoulder 17 on the interior of the outer barrel 10 to rotatably support the inner barrel 15 in the outer barrel. The inner barrel 15 is spaced from the interior of the outer barrel 10 to leave an annular fluid passage 18 for conducting the circulation fluid downwardly. Ports 19 are provided in the collar 16 to conduct the 35 circulation fluid from the passage 18 to ports 20 in the head 11. The ports 20 discharge the circulation fluid to the cutters of the drill, as will be subsequently described. A core catcher 21 is arranged in the head 11 to trap and retain the core. The core catcher 21 is an annular member or assembly and includes a plurality of circumferentially spaced spring urged dogs 22 projecting inwardly to bite into the core. The core catcher 21 is arranged between the shoulder 13 and a downwardly facing shoulder 23 in the 40 collar 16.

In accordance with the invention the lower portion of the head 11 is formed to receive the cutters and their mounting means. Spaced recesses 24 and 25 extend upwardly in the wall of 45

the tubular head 11 from its lower end. The inner and outer sides of the recesses 24 slope downwardly and inwardly with respect to the central longitudinal axis of the drill. A tapered 5 boss 26 is provided on the inner wall of each recess 24 to increase the thickness of the inner wall portion of the head 11 adjacent the recesses. Notches 27 extend upwardly from the lower end of the head 11 in the inner wall portion of the 10 head to connect or join the recesses 24 with the head opening 12. The notches 27 have flat substantially vertical side walls. Similar flat walled notches 28 are provided in the outer wall portions of the head 11 and join or communicate 15 with the recesses 24. The upper walls of the notches 27 and 28 are inclined downwardly and outwardly with respect to the central vertical axis of the drill and the notches 27 and 28 are radially aligned with respect to said axis. The 20 recesses 25 are spaced between the spaced recesses 24 and their inner and outer walls are flat and inclined downwardly and outwardly relative to the vertical axis of the drill. A tapered boss 29 is provided on the outer wall of each 25 recess 25 to increase the outer wall portion of the head 11 at the recesses. Notches 30 extend upwardly from the bottom of the head 11 in said outer wall portions of the head and join the recesses 25. The side walls of the notches 30 are 30 flat and substantially vertical. Notches 31 are provided in the inner wall portions of the head 11 and connect the recesses 25 with the head opening 12. The notches 31 have flat substantially vertical walls and the notches 30 and 31 35 are substantially radially aligned. The upper walls of the notches 30 and 31 are inclined downwardly and inwardly with respect to the central vertical axis of the drill.

The improved core drill construction of the 40 present invention includes, generally, inner roller cutters A, bearing means for rotatably mounting the cutters A in the recesses 24, outer roller cutters B and bearing means for rotatably mounting the cutters B in the recesses 25. We 45 will first proceed with a detailed description of one of the cutters A and its bearing means.

The cutters A are provided to assist in making an annular cut in the earth formation at the 50 bottom of the well bore and serve to trim the core for reception in the head opening 12. The several cutters A may be identical and the following description is equally applicable to all of the cutters A. The cutter A has a central longitudinal opening 32 and the ends of the cutter A 55 are preferably flat. The cutter A is cylindrical and is provided with suitable peripheral cutting parts or teeth 33. A central tapered socket 34 is provided in the inner end of the cutter A. In accordance with the invention axially spaced ball 60 races are provided in the wall of the cutter opening 32. In the preferred construction illustrated there are two spaced ball races 35 in the wall of the cutter opening 32. The races 35 are partially circular in cross section and are of 65 substantial depth.

The bearing means for rotatably supporting the inner cutters A each includes, generally, a pin 36, a sectional bushing 37 on the pin 36 and series of balls 38 cooperating with the races 35 70 and the bushing 37 to rotatably support the cutter A.

The bearing pin 36 may be a simple cylindrical member, as illustrated. The pin 36 is preferably uniform in diameter throughout its length. The 75 inner end of the pin 36 relative to the central

vertical axis of the drill is flat and pitched with respect to the axis of the pin. The pin 36 passes through the opening 32 of the cutter A and is considerably longer than the cutter.

The bushing 37 is assembled on the pin 36 and extends through the cutter opening 32 to project beyond the opposite ends of the cutter. In accordance with the invention the bushing 37 is sectional and comprises an inner section 40, a central section 41 and an outer section 42. The bushing sections 40, 41 and 42 are tubular and surround the pin 36. The bushing sections 40, 41 and 42 are generally cylindrical and may be of the same diameter. The several sections of the bushing 37 are arranged in end to end relation and the bushing is of the same length as the pin 36. The end of the section 40 at the inner end of the pin 36 is flat and has the same inclination as the end of the pin. The bushing section 42 has its outer end in the same plane 20 as the outer end of the pin 36. The inner bushing section 40 has two flat parallel side faces 43 extending inwardly from its inclined end. The outer bushing section 42 has two similar flat side faces 44 extending inwardly from its flat 25 outer end. The sections 40, 41 and 42 of the bushing 37 are arranged in abutting relation and in the preferred construction tapered bosses 45 are provided on the ends of the central section 41 and are received in sockets in the inner ends 30 of the sections 40 and 42.

It is an important feature of the invention that the sectional bushing 37 is secured or retained on the pin 36 against displacement therefrom whereby the cutter A and its bearing means 35 may be handled, shipped and installed as a unit. The inner and outer ends of the pin 36 are peened over or riveted over at 46 and 47 respectively to cooperate with the contiguous ends of the bushing sections 40 and 42, respectively. If desired, 40 the outer ends of the bushing sections 40 and 42 may be slightly counter-bored to receive the riveted over parts 46 and 47. The peened over or riveted over end parts 46 and 47 of the pin 36 cooperate with the bushing sections 40 and 42 45 to maintain the assembly of the several bushing sections in proper end to end relation on the pin 36.

The bushing 37 is provided with races to oppose the races 35 on the interior of the cutter A. 50 The outermost corner of the inner bushing section 40 and the abutting corner of the central bushing section 41 have annular grooves which register to form a ball race 48. The ball race 48 is partially cylindrical in cross section and 55 directly opposes one of the races 35. The corners of the sections 41 and 42 at their abutting ends are provided with annular grooves which register to form a ball race 49. The ball race 49 is partially cylindrical in cross section and 60 directly opposes the other race 35 on the interior of the cutter A.

The balls 38 rotatably mount or support the cutter A on the sectional bushing 37. The balls 38 are arranged in the pairs or sets of opposing races 35 and 48 and 35 and 49. The races 35 and 48 and 35 and 49 are shaped to accurately conform to the balls 38 whereby the load capacity of the bearing is increased. Owing to the depth of the races 35, 48 and 49, the rows or 70 series of balls 38 assume the end thrusts in both directions, as well as the radial thrusts. Thus the cutter A is supported solely or entirely by the balls 38. A notch 50 is provided in the central bushing section 41 and communicates with the 75

race 48 to facilitate the insertion of the balls 38 in the opposing race 35.

In assembling the cutter A and its bearing a series of balls 38 may be arranged in the outermost race 35 and the bushing sections 41 and 42 inserted in the cutter opening 32 from its opposite ends whereby the balls are properly retained in the races 49 and 35. The balls 38 are then successively inserted through the notch 50 into the other race 35 and when the required number of balls has been arranged in place the bushing section 40 is inserted in the cutter opening 32 to complete the race 48. The end parts 46 and 47 of the pin 36 may then be peened over or riveted over to secure the bushing sections 40, 41 and 42 against endwise movement and separation. The balls 38 cooperating with the opposing races 35 and 48, and 35 and 49, hold the cutter A against longitudinal movement and the end parts 46 and 47 of the pin 36 hold the bushing 37 against displacement from the pin. Thus the several parts of the assembly are secured against separation whereby the assembly may be readily handled as a unit.

The invention provides simple yet very dependable means for securing the bearing of the cutter A to the head 11. The assembly of the cutter A and its bearing assembled in the form of a unit, as described above, is moved upwardly relative to the head 11 to enter the cutter A in one of the recesses 24. When the cutter is thus entered in the recess 24 the projecting portion of the bushing section 42 is received in the notch 28 and the projecting portion of the bushing section 40 is received in the notch 27. The flat surfaces 34 and 44 may shiftably or slidably engage the flat side walls of the notches 27 and 28. The cutter assembly or unit is moved upwardly to bring the bushing sections 40 and 42 against the inclined upper walls of the notches 27 and 28. The cutter assembly is then moved inwardly so that the socket 34 receives the boss 26. A washer 51 is provided to occupy the space between the outer end of the cutter A and the adjacent wall of the recess 24. The washer 51 is in the nature of a C-washer so that it may be readily passed upwardly over the bushing section 42. When the cutter assembly and the washer 51 are in place the unoccupied portions of the notches 27 and 28 are filled with welds 52 and 53, respectively. The weld 52 securely connects the pin 36 and the section 40 to the inner wall portion of the head 11 while the weld 53 rigidly secures the C-washer 51, the bushing section 42 and the pin 36 to the outer wall portion of the head 11. The welds 52 and 53 may be ground or machined off smooth with the adjacent surfaces of the head 11.

The bushing sections 40 and 42 engage upwardly against inclined upper walls of the notches 27 and 28 so that the cutter A secured to the head 11, as just described, is rotatable about an axis inclined downwardly and outwardly relative to the vertical axis of the drill. The cutter A is mounted to project downwardly beyond the lower end of the head 11 and to project inwardly somewhat at the lower end of the opening 12 to assist in making the annular cut in the earth formation and to trim the core for reception in the drill.

The outer cutters B are provided to cut the well bore to gauge. The cutters B are frusto-conical having tapered or pitched peripheries. Suitable cutting teeth 55 are provided on the frusto-conical cutters B. The cutters B have flat ends and each is provided with a central longitudinal open-

ing 56. A tapered socket 57 is provided in the outer end of each cutter B to receive a boss 29. In accordance with the invention spaced ball races 58 are provided in the cutters B. In practice there may be two spaced ball races 58 provided in the wall of each cutter opening 56. The races 58 are partially circular in cross section and are of substantial depth.

The bearing means for rotatably supporting the outer cutters B are very similar to the means for supporting the inner cutters A. We will proceed with a description of the bearing means for supporting one of the outer cutters B, it being understood that such description is equally applicable to the bearing means of the other cutters B.

The means for rotatably supporting an outer cutter B includes a pin 60, a sectional bushing 61 on the pin and balls 62 cooperating with the races 58 and the bushing 61. The pin 60 is preferably a simple cylindrical member of uniform diameter. The ends of the pin 60 are flat and the outer end of the pin is pitched to be substantially vertical when the cutter assembly is in place on the head 11. The inner end of the pin 60 is pitched to be inclined downwardly and outwardly when the cutter assembly is secured in place on the head 11.

The bushing 61 is sectional and comprises an outer section 63, a central section 64 and an inner section 65. The sections 63, 64 and 65 are tubular and surround the pin 60. The sections 63, 64 and 65 are generally cylindrical and of uniform diameter. The outer end of the section 63 is pitched to lie in the same plane as the outer end of the pin 60. The section 64 has its exposed end pitched to lie in the same plane as the inner end of the pin 60. The sections of the bushing 61 are arranged in abutting end to end relation. In accordance with the invention the sectional bushing 61 is locked or retained on the pin 60 whereby the cutter and bushing assembly may be handled as a unit. The pin 60 has end parts 60^a and 60^b peened over or riveted over to engage the exposed ends of the bushing sections 63 and 65, respectively. The riveted over parts 60^a and 60^b of the pin 60 prevent endwise displacement of the bushing 61 from the pin. The sectional bushing 61 is longer than the cutter B and the projecting portions of the sections 63 and 65 are received in the notches 30 and 31. The bushing sections 63 and 65 preferably have flat side surfaces for cooperating with the side walls of the notches 30 and 31.

Registering grooves are provided in the corners of the abutting ends of the sections 63 and 64 to form an annular ball race 66. The ball race 66 directly opposes one of the races 58 in the cutter B. The corners of the abutting ends of the sections 64 and 65 have registering grooves which form an annular ball race 67 directly opposing the other ball race 58. The races 66 and 67 are partially circular in cross section and are of substantial depth. The balls 62 are provided in the sets or pairs of opposing races 58 and 66 and 58 and 67 and serve to rotatably support the cutter B on the sectional bushing 61. The opposing races are of such depth that the balls 62 transmit the end thrusts in both directions as well as the radial thrusts. A notch 78 is preferably provided in the section 64 to facilitate the assembly of the balls 62 in the adjacent race 58.

When the cutter B is to be assembled on the head 11 the cutter unit or the assembly of the cutter and its bearing is moved upwardly relative to the head 11 to enter the cutter B in a recess 75

25 and to enter the protruding flat sided portions of the bushing sections 63 and 65 in the notches 30 and 31, respectively. The cutter assembly is then moved outwardly to a position where the boss 29 is properly received in the recess 54. It is to be understood that the cutter B has proper clearance with the boss 29 and the walls of the recess 25 when in the final position. The protruding portions of the bushing sections 63 and 10 65 are engaged against the inclined upper walls of the notches 30 and 31. A C-washer 69 is provided to occupy the space between the inner end of the cutter B and the inner wall of the recess 25. The C-washer 69 is readily passed upwardly 15 around the bushing section 65 to engage against the wall of the recess 25 and to have proper clearance with the cutter B. When the cutter assembly is in its proper position the unoccupied portions of the notches 30 and 31 are filled with welds 20 70 and 71, respectively. The weld 70 rigidly secures or bonds the bushing section 63 and the pin 60 with the outer wall portion of the head 11 while the weld 71 fixes the washer 69, the bushing section 65 and the pin 60 to the inner wall portion 25 of the head 11. The welds 70 and 71 may be finished to be flush with the adjacent surfaces of the head 11.

It is believed that the utility and practicability of the drill construction provided by this 30 invention will be readily apparent from the foregoing detailed description. The cutters A and B are supported entirely by the sets or series of balls 38 and 62 to rotate with a minimum of friction. The bearing assemblies are securely 35 welded in the notches of the head 11 to positively prevent loss or displacement of the bearing parts and cutters. The cutter and bearing assemblies may be assembled at the place of manufacture and constitute units that may be shipped, handled and installed with ease. These cutter and bearing assemblies may be properly assembled at the place of manufacture to accurately fit the drill head 11.

Having described only a typical preferred form 40 and application of our invention, we do not wish to be limited or restricted to the specific details herein set forth, but wish to reserve to ourselves any variations or modifications that may appear to those skilled in the art or fall within the scope of the following claims:

Having described our invention, we claim:

1. A cutter unit in a well drilling tool comprising, a cutter having an opening, a pin passing through the opening, a bushing on the pin, balls rotatably supporting the cutter on the bushing, and riveted over parts on the pin holding the bushing on the pin whereby the assembly may be handled as a unit.
2. A cutter unit for a well drilling tool comprising, a cutter having an opening, a pin passing through the opening, a bushing on the pin, balls rotatably supporting the cutter on the bushing and transmitting both the end thrusts and the radial thrusts between the bushing and cutter, and parts on the pin at the ends of the bushing peened over to hold the bushing on the pin.
3. In a well drilling tool, an assembly adapted 70 to be handled as a unit comprising a cutter having an opening, a pin passing through the opening, a sectional bushing on the pin, there being opposing ball races in the bushing and the interior of the cutter, balls cooperating with races to rotatably support the cutter, and riveted over

parts on the pin holding the bushing against displacement from the pin.

4. In a well drilling tool, an assembly adapted to be handled as a unit comprising a cutter having an opening, a pin passing through the opening, a sectional bushing on the pin, there being opposing ball races in the bushing and the interior of the cutter, balls cooperating with races to rotatably support the cutter, the races being of such depth that the balls transmit end thrusts 10 between the bushing and cutter, and riveted over parts on the pin holding the bushing against displacement from the pin.

5. In a well drilling tool, an assembly adapted to be handled as a unit comprising a cutter having an opening, a pin passing through the opening, a sectional bushing on the pin, there being opposing ball races in the bushing and the interior of the cutter, balls cooperating with the races to rotatably support the cutter, and end 15 parts on the pin riveted over against the ends 20 of the bushing.

6. A well drilling tool comprising a body, a cutter having an opening, a ball bearing in the opening rotatably supporting the cutter and assuming end thrusts from the cutter in both directions, and welding securing the bearing to the body.

7. A well drilling tool comprising a body, a cutter having an opening, a pin extending into the opening, a bushing on the pin, balls rotatably supporting the cutter on the bushing, and a weld securing the pin to the body.

8. A well drilling tool comprising a body, a cutter having an opening, a pin extending into the opening, a bushing on the pin, balls rotatably supporting the cutter on the bushing, and a weld securing the bushing to the body.

9. A well drilling tool comprising a body, a cutter having an opening, a pin extending into the opening, a bushing on the pin, balls rotatably supporting the cutter on the bushing, and a weld securing the pin and bushing to the body.

10. A well drilling tool comprising a body having spaced supports, a cutter between the supports having an opening, a pin extending through the opening, a ball bearing on the pin rotatably supporting the cutter, and welds securing the bearing to the supports.

11. A well drilling tool comprising a body having spaced supports, a cutter between the supports having an opening, a pin extending through the opening, a sectional bushing on the pin, balls cooperating with the bushing and the cutter rotatably supporting the cutter and transmitting the end thrusts between the cutter and bushing, and welds securing the pins to the supports.

12. In a well drill, spaced supports having openings, a cutter between the supports having an opening, a bearing extending through the opening in the cutter and having its end portions received in the first mentioned openings, balls rotatably supporting the cutter on the bearing, and welds securing the said bearing portions in the said first mentioned openings.

13. In a well drill, spaced supports having notches, a cutter between the supports having an opening, a pin extending through the opening, a bushing on the pin having its end portions received in the notches, the bushing and cutter opening having opposed races, balls in the races rotatably supporting the cutter, and welding securing the said end portions of the bushing in the notches.

14. In a well drill, spaced supports having notches, a cutter between the supports having an opening, a pin extending through the opening, a bushing on the pin having its end portions received in the notches, the bushing and cutter opening having opposed races, balls in the races rotatably supporting the cutter, a washer on the bushing between one of said supports and the cutter, a weld in the notch of said support securing the washer and the adjacent end portions of the bushing and pin to said support, and a weld in the notch of the other support securing the adjacent end portions of the bushing and pin to said other support. 5
- 10 15. In a well drill, spaced supports having notches, a cutter between the supports having an opening, a pin extending through the opening, a bushing on the pin having its end portions re-

ceived in the notches, the bushing and cutter opening having opposed races, balls in the races rotatably supporting the cutter, a washer on the bushing between one of said supports and the cutter, a weld in the notch of said support securing the washer and the adjacent end portions of the bushing and pin to said support, and a weld in the notch of the other support securing the adjacent end portions of the bushing and pin to said other support. 10
